 R. H. Ladd,

UNITED STATES PATENT OFFICE.

PORTER E. CUMMINGS, OF SANFORD, MAINE.

IMPROVED KNIFE-CARRIER.

Specification forming part of Letters Patent No. **58,992**, dated October 23, 1866.

To all whom it may concern:

Be it known that I, PORTER E. CUMMINGS, of Sanford, in the county of York and State of Maine, have made a new and useful invention having reference to Knife-Carriers of Sole-Cutting Machines, and particularly to that as used in the machine described in No. 43,958 of United States Patents; and I do hereby declare the same to be fully described in the following specification and represented in the accompanying drawings, of which—

Figure 1 denotes a side elevation, and Fig. 2 an edge elevation, of a knife and its carrier as formed in one piece, such being the mode heretofore adopted of constructing the same, my invention being an improvement thereon. Fig. 3 is a top view, Figs. 4 and 5 side elevations, Fig. 6 an edge elevation, Fig. 7 a vertical and longitudinal section, and Fig. 8 a vertical and transverse section, of a knife and its carrier made in accordance with my invention, by which the knife and its carrier are in two separate parts, and the carrier is formed with a socket and a rabbet to receive the knife, and is provided with a clamp or set screw to hold it in such socket.

After the knife-carrier has been once fixed and adjusted in the machine, its removal for the purpose of sharpening the knife often renders it difficult or requires a considerable expenditure of time and labor to readjust it properly. It is therefore desirable always to

keep the knife-carrier in its proper place in the machine, and for this purpose I make it separate from the knife, and with a socket and a rabbet to receive the shank of the hinge.

In Figs. 3, 4, 5, 6, 7, and 8, A represents the knife, and B the carrier; a, the journal; b, the socket; c, the rabbet, and d the clamp-screw of the carrier. The knife is to be made with a shank, e, to fit to and extend down into the socket. The screw screws into the carrier and against the knife. The rabbet goes across the socket, and allows the face of the knife to rest closely against the edge of the pattern. It also constitutes a shoulder to rest against the lower surface of the pattern and as a means of preventing the edge of the knife from cutting into the edges of the pattern.

With my invention the knife can be easily removed from the carrier without the necessity of removing the latter from the machine.

I claim—

The improved knife-carrier made substantially as described—viz., with the knife-shank socket and the rabbet arranged in it as set forth, the said carrier being provided with a set-screw, or equivalent means of fixing the knife-shank in the socket.

PORTER E. CUMMINGS.
